UNITED STATES PATENT OFFICE.

FREDERIC E. GARDNER, OF BELOIT, WISCONSIN.

GRINDING MACHINE.

Original application filed May 27, 1921, Serial No. 472,977. Divided and this application filed July 20, 1925. Serial No. 44,729.

This invention relates to improvements in mountings for tool spindles, and has particular reference to spindles for supporting disk grinders. The present application is a 5 division of my copending application Serial No. 472,977, filed May 27, 1921.

The invention is particularly adapted for use in double disk grinders in which two grinding wheels or disks are arranged in 10 opposed relation with the spindles co-axial or parallel. Work is fed between the two parallel grinding faces of the wheels to grind the same simultaneously on opposite sides in parallel planes.

15 A general object of the invention is to provide means for universally adjusting the axis of one of the grinding wheels to position the faces of the two wheels in exact parallelism. Where but one grinding wheel 20 is provided the adjustment is available to bring the face of said wheel into a predetermined or desired plane.

This object and other objects, which will 25 become apparent as the description proceeds, are attained in the machine shown in the accompanying drawings, but I would have it understood that this particular machine represents only one of many possible embodiments of my invention, and that while I have 30 shown and will hereinafter describe the said particular embodiment in detail for the sake of lucidity, I do not intend to limit the invention to the construction disclosed, but aim to cover in the appended claims all 35 modifications and equivalents falling within the scope of my invention as determined by the state of the prior art.

In the accompanying drawings, Figure 1 40 is a side elevational view of a grinding machine embodying my invention.

Fig. 2 is a fragmentary sectional view taken along line 2—2 of Figure 1.

Fig. 3 is a fragmentary vertical sectional view of the adjustable mounting for one of 45 the grinding spindles.

Figs. 4 and 5 are elevational views partially in section of the right and left ends respectively of the mounting shown in Fig. 3.

Fig. 6 is a plan view of a support forming 50 part of said mounting.

In the grinding machine disclosed in the parent application, two main carriages are arranged in offset relation on a main bed or base. In these carriages are rotatably mounted two spindles on the adjacent ends 55 of which are fixed grinding wheels or disks. These grinding wheels preferably are of the so called ring wheel type, and are arranged with their adjacent edges overlapping to the extent of their radial dimensions. Between 60 the opposed faces of the grinding wheels is a carrier preferably in the form of a rotary disk, having receptacles to carry pieces of work into the space between the grinding wheels. One of the carriages is mounted 65 to reciprocate axially of the spindle thereby to move its grinding wheel toward and away from the carrier to facilitate the introduction of work between the wheels. Automatic means is provided for reciprocating this 70 grinding wheel, and for moving the work carrier in timed relation thereto so that when the wheels are separated a piece of work may be interposed between the two grinding faces. 75

Means is provided for universally adjusting the axis of the other or stationarily mounted grinding wheel to effect parallelism between the grinding faces of the wheels, which adjusting mechanism comprises means 80 for moving the bearings for grinding wheel spindle about a horizontal and a vertical axis independently.

Referring to Figure 1 of the drawings, a suitable base 10 carries on its opposite ends 85 two carriages 11 and 12 having bearings in which two spindles 13 and 14 are mounted, said spindles having fixed to their adjacent ends two grinding wheels which are indicated as a whole by numerals 15 and 16. 90 The spindles have pulleys 17 and 18 fixed thereon by which they may be driven from any suitable source of power. The axes of the two spindles 13 and 14 are parallel, but are offset or arranged out of alignment 95 with each other, both axes being in the present instance in the same horizontal plane.

Between the wheels 15 and 16 there is mounted a rotatable work carrier 19 adapted 100

to receive work pieces in suitable holes 20 uniformly spaced about its periphery and carry them down between the grinding wheels. As the piece of work is carried 5 down between the opposed faces of the grinding wheels by rotation of the carrier, the carriage 11 is automatically drawn back to let the piece of work enter freely. After the piece of work is completely between the 10 opposed portions of the faces of the grinding wheels, the carriage 11 is automatically fed in and the piece is ground to an exact thickness. The carriage is then drawn back again and the finished piece of work is discharged. The means for automatically operating the work carrier and reciprocating the movable carriage 11 forms no part of the present invention and is disclosed in the above-mentioned parent application.

20 Means is provided for obtaining perfect alinement or parallelism of the axes of the two grinding wheels by adjustment of the second carriage 12. A knee 21 is journaled on a horizontal axis at 22 on the base 10 of the machine. This knee is supported at 25 its outer end by a pair of jack screws 23 secured by lock nuts, and is clamped by a bolt 24 which passes through upstanding lugs 25 on the base 10 and through elongated holes 30 26 in the overlapping sides of the knee. A sub-base 27 is supported upon the knee 21 to swing about a pivot 28 located at one end of the knee and sub-base, and the sub-base is 35 adapted to be clamped in position on the knee by four bolts 29 passing through enlarged or elongated openings 30 in the sub-base and threaded into the knee. When these bolts are loosened, the sub-base 27 may be swung on the vertical axis of the pivot 28, and by tightening the bolts the sub-base may be locked in its set position. Suitable upstanding lugs 31 at opposite sides of the knee 21 carry adjusting bolts 32 by 40 means of which the sub-base may be conveniently and accurately adjusted. It will thus be seen that the two adjustments about the pivotal axes 22 and 28 provide for perfect alinement or parallelism of the faces of the two grinding elements 15 and 16.

50 For adjusting the grinding element 16 with respect to the work, the carriage 12 is slidably mounted with respect to its sub-base 27 on guides 33. The means herein shown for making this adjustment comprises a combined nut and worm wheel 34, the periphery of which meshes with a worm 35, the nut being positioned between opposed walls or lugs on the carriage and receiving a screw shaft 36. This shaft is rotatably mounted in a lug 37 on the sub-base 27, and has collars 38 to prevent endwise movement thereof.

55 For quick adjustment of the grinding element toward and away from the work, the shaft 36 is rotated within the worm wheel 34

by means of a suitable crank handle (not shown) which may be applied to the outer squared end of said shaft. A slower and more accurate adjustment is obtainable by clamping the shaft 36 by means of a split bearing 39, and by rotating the worm wheel nut 34 by means of the worm 35. The worm is rigid with a shaft 40 which is mounted in a lug 41 on the carriage 12, and is held against longitudinal movement by said lug, 75 said shaft being provided with a hand wheel 42 by means of which the worm 35 may be rotated.

By virtue of the various adjustments provided for the carriage 12 supporting the 80 grinding wheel structure, the faces of the two grinding wheel elements can be accurately kept in parallel planes so that accurate grinding will result.

I claim as my invention:

1. A grinding machine having, in combination, a main base, a support pivotally mounted thereon to swing in one direction, means for adjustably fixing said support in different positions, a second support pivotally mounted on the first support for adjustment in a different direction, means for adjusting the second support into different positions with relation to the first support, a carriage slidable on the second support, and a rotary grinding element mounted on said carriage.

2. A grinding machine having, in combination, two opposed grinding elements, means for feeding one of said grinding elements toward and away from the other, and means for adjusting the other grinding element into correct relative position with respect to said first-mentioned grinding element by pivotal adjustment independently around a horizontal and around a vertical axis.

3. In a grinding machine, in combination with an automatically reciprocable grinding element, a second grinding element opposed to said reciprocable element, and means for adjusting said last-mentioned grinding element into perfect alinement with respect to said reciprocable element by adjustment independently around each of two perpendicular axes.

4. In a grinding machine of the class described, the combination of a base, a support hinged at one end to said base to swing vertically, a guide frame mounted on said support to be swung laterally, a carriage shiftable on said frame, a shaft journaled in said carriage, and a grinding wheel on said shaft.

5. In a grinding machine of the class described, the combination of two shafts, a grinding wheel at the end of each shaft with the wheels opposed to each other, means for adjusting one of said shafts by vertical swing thereof, and means for adjusting said

shaft by horizontal swing thereof whereby said wheels may be relatively alined.

6. In a grinding machine of the class described, the combination of two shafts, a grinding wheel at the end of each shaft with the wheels opposed to each other, means for adjusting one of said shafts by

vertical swing thereof, means for adjusting said shaft by horizontal swing thereof, to relatively position said wheels, and means for shifting said shafts longitudinally. ¹⁰

In testimony whereof, I have hereunto affixed my signature.

FREDERIC E. GARDNER.
